UNITED STATES PATENT OFFICE.

GLENN H. NILES, OF RIDGEFIELD PARK, NEW JERSEY, ASSIGNOR TO THE IMPROVED EQUIPMENT COMPANY, OF NEW YORK, N. Y., A CORPORATION OF COLORADO.

RETORT-BENCH.

1,185,602.

Specification of Letters Patent. Patented May 30, 1916.

Application filed May 11, 1914. Serial No. 837,871.

To all whom it may concern:

Be it known that I, GLENN H. NILES, a citizen of the United States, residing at Ridgefield Park, in the county of Bergen and State of New Jersey, have invented certain new and useful Improvements in Retort-Benches, of which the following is a specification.

This invention relates to retort benches; 10 and it comprises a carbonizing and gas making apparatus, such as a gas bench, provided with one or more sectional retorts and supporting means for holding said retorts and their sections in locked engagement, said 15 means comprising a particular type of collar or flange on the several sections of the retort or on one or more of segments constituting such sections; all as more fully hereinafter set forth and as claimed.

20 It is often desirable to use an inclined type of retort or oven in gas benches in carbonizing coal for making illuminating gas, thereby securing a gravity-aided feed of coal therethrough; but there are a number of 25 mechanical disadvantages attendant on the use of this type. The whole thrust of the retort is directly downward and outward against one wall of the combustion chamber or housing surrounding the retorts, and the 30 retorts have a further tendency to creep with expansion and contraction under changes of temperature. This renders it difficult to provide a firm and permanent setting for inclined retorts of the usual types. Whatever 35 type of vertical supports, intermediate the ends of the retort be used it is difficult to distribute the load of the retorts upon them in the way practicable with horizontal retorts. In the prior art attempts have been 40 made to obviate this by providing recesses or a pair of spaced lugs or the like on the retorts at intervals to engage the intermediate supports. This however does not have the desired result since if the lugs or recesses 45 fit the vertical supporting member closely the latter receives the side thrust of the weight of the retort and if they do not fit closely there is no special function to the lugs.

50 Formerly retorts were generally integral; were made of a single body of ceramic material, iron, etc. Latterly, there have come into use built-up retorts made of slabs or segments of refractory material with the 55 joints united by a lute or cement. This

enables the use for retorts of highly refractory silica or silicious materials which could only be with difficulty made into an integral retort of large size. These materials are highly refractory and they are better heat 60 conductors than clay. Generally these retorts are composed of several sections in end-to-end abutment and each of these is in turn composed of slab-like segments of such form that when they are laterally united 65 they give a retort of the usual shape. These built-up retorts are however mainly used in a horizontal position since their sectional structure adds new difficulties to those already incident to the employment of inclined retorts. 70

It is one of the objects of the present invention to enable the utilization of the advantages of these sectional silica retorts in inclined retort benches. To this end, in 75 making the retorts I provide the several sections of each retort at one or both ends with a flange-like collar of a shape giving horizontal bearing surfaces above and below in the inclined position of the retort and provide vertical supporting elements not only adapted to engage these bearing surfaces in such manner as to give a direct upward support but also adapted to give a sidewise locking engagement holding the section segments in place in the supporting walls of the bench. With this structure, the built-up 80 formation of the retorts is not only not a disadvantage in an inclined bench but is an advantage since it enables a good distribution 85 of thrusts. In effect, each section, or sub-retort, may be independently supported at its ends and by stepping the abutting ends, the joints may be sealed in an advantageous way. 90

Advantageously, for my purposes the retorts are made of as many sections along their length as there are intended to be vertical supports, with the joint or seam coming at the point of support. This enables 100 the support to cover the joint and permits a relatively loose mutual engagement of the several sections with a slight amount of end-to-end play, giving room for separate expansion and contraction without necessitating movement of the retort as a whole. This subdivides the total end thrust. These sections in turn may be, and advantageously are, made up of a plurality of longitudinal 105 segments or slabs having interlocking sides 110

and in engagement forming an annular D-shaped retort of the usual shape. I have found that if I mold these several retort sections in such a way as to give a liplike flange or collar at the end, each such flange having an upper and a lower face which will be horizontal in the usual inclined position of the retort, that I can assemble retorts with supporting and spacing elements having corresponding faces and located between the lower and upper retorts in such a way as to secure the desired good vertical support at intervals along the line of the retort, distributing the thrusts which otherwise would come on the front wall of the gas bench; the shape of such a flange allowing the conversion of longitudinal thrust into vertical thrust. In other words, being taken up by the spacing and supporting elements, the thrust of each section instead of being in part longitudinal is converted into vertical thrust and is transferred to the vertical support formed by the liplike flanges and the connecting and spacing elements. These connecting or tile sections allow the retorts to be spaced apart to secure good heat distribution. With a plurality of superimposed retorts in an ordinary gas bench, at the abutting ends of sections of the retorts, there is an intermediate vertical support engaging the liplike flanges.

The end flanges of the several sections or sub-retorts may be, and advantageously are, continuous around the ends of the sections to form a flange collar, thereby enabling a side support in much the same way to lock the component segments in place. The flange may be of the same height at all points and extend out from the body of the retort an equal distance all around but more advantageously it diminishes in height toward the middle of the sides of the retort, giving a more nearly vertical side surface for engagement with lateral supporting segment-locking members. The tendency of the weight of the retort, and of the weights resting on the retort, is to produce flattening out or spreading of the retort and with these built-up retorts the side locking member under the present invention is useful as taking stress off the luted or cemented joints.

The described invention may of course be applied to any number of retorts assembled together in any suitable gas bench or to a single retort, carbonizing chamber or oven, and may be applied to sectional and segmental retorts of other material than silica.

In the accompanying illustration I have shown, more or less diagrammatically, an embodiment of my invention.

In this showing Figure 1 shows a 9-retort gas bench in vertical transverse section with certain parts in elevation of the structure

of Fig. 2, the section on the left being along line A—A and that on the right being along line B—B of Fig. 2; Fig. 2 is a vertical longitudinal section along line E—E of Fig. 1; Fig. 3 is an end elevation of one of the retort sections or sub-retorts; Fig. 4 is a fragmentary side view of three sections assembled; Fig. 5 is a fragmentary vertical transverse section of a carbonizing oven or apparatus carrying a single retort; and Fig. 6 is a vertical longitudinal view of the same.

In the illustration, the showing of Figs. 1 and 2 is of a gas bench having the usual heating means. Nine inclined retorts arranged in three vertical tiers are shown. Each retort is built of a number of sub-retorts or sections (10 are shown) 1 united end-to-end along its length and each of these sections in turn is built up of a plurality of tongued and grooved slabs or segments 2. As shown, there is a division of the fire chamber into a plurality of separate sub-chambers, there being as many as there are retort sections, and the division being effected by a corresponding number of tile walls. These tile walls have the double function of supporting the section ends, each adjacent pair of section ends meeting in a tile wall, and of forming these sub-chambers. The tile walls, which support and side-lock the section ends, may be formed of as many coöperating tile members as may be necessary, the shape of these members of course varying somewhat with the number employed. As shown (see Fig. 1), there are two tile members between vertically adjacent sections and four between laterally adjacent section ends. More or fewer coöperating tile members may be used, but the number of tiles and the shapes shown are convenient. These tile walls fit closely to the top and bottom of the section ends which they engage, closing off the sub-chambers between the walls from communication at this point; but the several members of which they are composed are so shaped and arranged as to take the weight of an engaging upper section and without communicating it to the section end next below, to transfer such weight laterally to the tile members forming the division between laterally adjacent retort sections. In effect the tile or tiles between vertically adjacent pairs of section ends form a weight-transmitting arch, as well as a spacing means and means for closing the sub-chambers mentioned. As will be apparent from an inspection of Fig. 1, the various tile sections are of such shape as to coöperate in securing the retorts in place. Tiles 5 between vertically adjacent retorts in one section (see Fig. 2) are advantageously of a Z-shape for a purpose later explained. At each end the retorts are provided with end

pieces 6, which may advantageously be of clay, of a shape adapted to engage with and continue the retorts, these end pieces being in and carried by walls 7 and 8. At the top, the vertical tile walls engage transverse elements 9 and 10 in such a manner as to secure them at the upper end and prevent backward thrust of the tile walls due to the sliding of the inclined joint between the roof 10 11 and the tile wall. As the retort stack tends to rise and fall somewhat by expansion and contraction this arrangement is advantageous.

Referring now mainly to Figs. 2 and 4, it will be seen that each of the retort sections is assembled with the next in line at abutting ends through a tongue-and-groove joint which may be filled with any suitable cement or lute, the forward end of each 20 section carrying a tongue 12 which engages a corresponding groove in the rear end of the next section. The tongue on the foremost section engages in a corresponding groove in the end piece while the end piece 25 at the other end of the retort carries a tongue 13 engaging a groove in the rear end of the last section. Each end of the section is provided with a lateral lug or flange projecting out of its general longitudinal line 30 and having horizontal bearing surfaces above and below and working out to a vertical bearing at the sides. This lug or flange at the top of the lower end of each section is designated (see Fig. 4) as 14 and at the 35 top of the upper end as 15 while that at the bottom of the lower end is 16 and that at the bottom of the upper end is 17. It will be observed that the faces of 14 and 15 and 16 and 17 at the abutting end of the two sections, are out of line or are staggered leaving a vertical face 18 forwardly presented and a vertical face 19 rearwardly presented at the meeting ends of the two sections. This allows the use of the Z-shaped tile (5) 40 between each vertical pair of retorts, forming a supporting means. The use of this tile between the upper and lower retorts allows them to be spaced apart vertically somewhat, allowing free access of fire gases 45 to the tops and bottoms of the retorts. This much conduces to good heating. Further with the character of joint indicated, if the two section ends are assembled a little loosely, as they advantageously may be, an 50 opportunity to work back and forth a little without disturbing the tightness of the joint is afforded. In a way, without interfering with the gas-tight qualities of the retort, it is converted into a plurality of vertically 55 supported independent sections; the vertical stress being communicated through the Z-shaped tiles and around the retorts to the base. The assemblage of tiles is best seen in Fig. 1. Special tiles 20 support the bottommost retorts. Mouthpieces 6 are suitably

contoured to engage Z-tile elements 21. Metal bars α reinforce the front wall. The slab-like segments (2) similarly engage with each other through tongue-and-groove joints; and the side segments are provided with a flange corresponding to that at the top and bottom. As shown in Fig. 3 it is somewhat reduced in elevation on these side flanges to give a more or less vertical bearing surface. This bearing surface engages 75 with intermediate lateral supporting and side supporting tiles 22 and 23. The tendency of the weight of the retorts and their contents is to cause a flattening and these side flanges give a locking support to 80 the segments which takes much of the stress off the tongue-and-groove joints between the segments and the cement therein. The joints between the lower sections may be, as shown in Fig. 3, radial, giving an arch formation, 85 or may be vertical, as shown in Fig. 1. As shown the gas bench is provided with the usual side walls 24 and recuperator elements (designated as a whole by 25) for 90 heating inflowing air.

In the structure of Figs. 5 and 6 the several elements are substantially the same as in Figs. 1 and 2; these figures showing the use of a single retort in a chamber instead of the nine retorts of Figs. 1 and 2. The 95 retort is supported and spaced from the walls of the heating chamber by side tiles 26, which has the same function as the tile walls in Figs. 1 and 2. The retort rests on elements 20 in the same manner as the lower 100 most retorts of Fig. 2.

What I claim is:—

1. In a gas bench, a retort composed of a plurality of multisegmental sections in mutual abutment, bearing flanges on said sections, vertical supporting wall members engaging the sections at the point of abutment and lateral wall members also engaging the sections.

2. In a gas bench, a plurality of inclined sectional retorts in superimposed relation, the abutting sections of each retort being provided at each end with a collar flange having bearing surfaces in substantially horizontal planes, vertical spacing and supporting means between vertically adjacent retorts having bearing surfaces engaging the collar flanges of both said vertically adjacent retorts, said spacing and supporting means each being arranged to receive the weight of the retort section above it and to transmit the strain of such weight laterally, and means for receiving said lateral strains.

3. In a gas bench, a plurality of inclined sectional retorts in superimposed relation, the abutting sections of each retort being provided at each end with a collar flange having bearing surfaces in substantially horizontal planes with the bearing surfaces of abutting flanges out of line, vertical spac-

- ing and supporting means between vertically adjacent retorts having bearing surfaces engaging the collar flanges of both said vertically adjacent retorts, said spacing 5 and supporting means each being arranged to receive the weight of the retort section above it and to transmit the strain of such weight laterally, and means for receiving said lateral strains.
10. 4. In a gas bench, a plurality of inclined sectional retorts spaced apart in vertical and horizontal series, the abutting sections of each retort being provided at each end with a collar flange having upper and lower 15 horizontal surfaces, tiles engaging such surfaces intermeshing each upper and lower retort section at the point of abutment of adjoining sections and serving to close the joint therebetween, and tile similarly located between laterally adjacent retorts and laterally engaging the collar flanges, said tiles being in thrust-receiving relationship to the first named tiles.
5. In a gas bench, a plurality of inclined 25 sectional retorts spaced apart in vertical and horizontal series, the abutting sections of each retort being provided at each end with a collar flange having upper and lower horizontal surfaces with the surfaces of 30 abutting flanges out of horizontal line, tiles engaging such surfaces intermeshing each upper and lower retort at the point of abutment of adjoining sections and serving to close the joint therebetween, and tiles similarly located between laterally adjacent retorts and laterally engaging the collar flanges, said tiles being in thrust-receiving relationship to the first named tiles.
6. In a gas bench, a plurality of inclined 40 retorts in vertical series, each such retort being composed of a plurality of multisegmental sections in mutual abutment and each such section carrying a flange at each end, vertical tile supporting members engaging each abutting pair of collars and covering the joint therebetween, intermediate members also serving as spacing means, and lateral tile members similarly 45 engaging and supporting the collars at the sides.
7. In a gas bench, a plurality of inclined retorts in vertical series, each such retort being composed of a plurality of multisegmental sections in mutual abutment and 55 each such section carrying a flange at the end, the abutting collars having horizontal surfaces out of line with each other, vertical tile supporting members engaging each abutting pair of collars and covering the joint therebetween, intermediate members also serving as a spacing means, and lateral tile members similarly engaging and supporting the collars at the sides.
8. In a gas bench, a plurality of inclined 60 retorts in vertical series, each such retort being composed of a plurality of multisegmental sections in mutual abutment and each such section carrying a flange at the end, vertical tile supporting members engaging each abutting pair of collars, intermediate members serving as spacing means, and lateral tile members similarly engaging and supporting the collars at the sides.
9. In a retort, a retort section composed 75 of laterally assembled longitudinal segments and provided with a flange collar at each end.
10. In a retort, a retort section composed 80 of laterally assembled longitudinal segments and provided with a flange collar at each end, said collar above and below having bearing surfaces at such an angle to the axis of the section as will adapt such surfaces to a horizontal position in an inclined position of the section.
11. In a retort, a retort section composed 85 of laterally assembled longitudinal segments and provided with a flange collar at each end, said collar above and below having bearing surfaces at such an angle to the axis of the section as will adapt such surfaces to a horizontal position in an inclined position of the section, and said collar having vertical faces on the sides of the section.
12. A gas bench comprising a plurality 90 of inclined retorts, intermediate vertical retort supporting walls spaced apart along the length of said retorts and longitudinal spacing members engaging said walls above 100 the tops of said retorts.
13. In a gas bench, a plurality of inclined retorts in vertical series, each of said retorts being in a plurality of abutting sections, the abutting ends being furnished with stepped collars, and a built-up sectional tile wall engaging and spacing apart said collars, the portion of the wall between the collars of upper and lower retorts closing the space therebetween and serving as an arch to support the weight of the upper retort and said wall also comprising an extension along the sides of the lower retort and receiving the thrust of said portion.
14. In a gas bench, a plurality of vertically spaced inclined retorts, and a plurality 105 of horizontally spaced inclined retorts, each such retort comprising abutting multisegmental sections, vertical spacing and supporting means located at the points of abutment in vertical series, and lateral separating means between retorts in horizontal series operating as locking supports for the segmental sections.
15. A retort bench comprising supporting walls, and an inclined retort therein, said retort comprising a plurality of abutting sections each consisting of adjoining 115

laterally united segments and being spaced and supported in said walls by vertical supporting means engaging the points of abutment of the sections and by lateral supporting segment locking members engaging the sides of the segments.

In testimony whereof, I affix my signa-

ture in the presence of two subscribing witnesses.
